[57] CLAIM

The ornamental design for an iron with steam unit, as shown and described.

DESCRIPTION

FIG. 1 is a perspective view of the top, front and one side of an iron with steam unit showing my new design;

FIG. 2 is a side elevational view of said one side, the opposite side being a mirror image thereof;

FIG. 3 is a top plan view thereof;

FIG. 4 is a bottom plan view thereof;

FIG. 5 is a front elevational view thereof; and,

FIG. 6 is a rear elevational view thereof.
